ILLUSION DEVICE

William H. Chandlee, Washington, D. C.

Application June 21, 1932, Serial No. 618,557
Renewed August 27, 1934

6 Claims. (Cl. 272—13)

This invention relates to new and useful improvements in illusion devices, and particularly to illusion devices which are especially adapted for use in show window advertising.

5 The principal object of the invention is to provide a device of this character wherein a person may perform acts to display articles of apparel, or the like, and wherein only that portion of the person, on which the articles are worn, may be 10 seen by the observer, normally.

Another object is to provide a device of this character wherein a portion of the person may be caused to disappear, and reappear, at will, while the remaining portions of the person remain in 15 plain view during the act of applying and removing the articles of apparel, or while walking around, to display the articles.

Other objects and advantages will be apparent from the following description when taken in 20 connection with the accompanying drawings:

In the drawings:

Figure 1 is a front elevation of the cabinet, forming the subject-matter of the present invention.

25 Figure 2 is a horizontal sectional view on the line 2—2 of Figure 1.

Figure 3 is a vertical central sectional view on the line 3—3 of Figure 2.

30 Figure 4 is a vertical transverse sectional view on the line 4—4 of Figure 2, looking toward the rear of the cabinet.

Figure 5 is a sectional view, similar to Figure 4, looking toward the front of the cabinet.

Figure 6 is a sectional view on the line 6—6 of 35 Figure 2.

Referring particularly to the accompanying drawings, there is shown a cabinet, represented as a whole by the numeral 10. This cabinet includes the longitudinal central compartment 11, and 40 the two side compartments 12, each of the latter being arranged at a side of the forward portion of the central compartment, and separated therefrom by the short vertical walls 13, above which are the openings 14, said walls rising from the floor 15, which is common to all of the compartments. Across the front of the cabinet is a wall 16, in the center of which is formed a vertical sight opening 17, permitting a view into the central compartment 11, the portions of said front 45 wall, at each side of said opening, inclining laterally and outwardly from the plane of said opening, as at 18. The central compartment 11 extends rearwardly beyond the rear walls of the side compartments 12, as shown in Figure 2. Supported on the rear face of a panel 20, which is

arranged above the forward portion of the central compartment 11, is a lamp 21, the lighting and extinguishing of which are controlled by a person who occupies the rear of the compartment 11, as will be explained later herein, for illuminating the rear of said compartment and the occupant. Depending from the ceiling, in each of the side compartments 12, is a lamp 22, and mounted in the upper portion of the front opening 17, in concealed position behind the depending 10 shield 23, is a lamp 24.

Suspended in the forward portion of the central compartment 11, in a plane slightly above that of the upper sides of the walls 13, by means of the bracket arms 25, mounted in said compartment, is a table or shelf 26, the rear of which is cut out to form a rectangular notch 27. Within this notch are secured the lower edges of the two vertical, right-angularly meeting transparent mirrors 28, said mirrors extending upwardly 20 to said ceiling, where their upper edges are properly secured therein. The rear vertical edges of the mirrors are secured within grooves 29, in the rear vertical walls of the side openings 14, just above the said bracket arms 25. A vertical strip of suitable material 30, is mounted to extend vertically between the surface of the table, at the front corner thereof, and the ceiling, said strip being longitudinally grooved at 31, to receive the front meeting edges of the mirrors, for the purpose of concealing said meeting edges from the view of the observer, standing in front of the cabinet, and to hide the fact that anything lies between the observer and the rear of the compartment 11, to obstruct his view.

Disposed on the table, in front of each of the mirrors, in position to be reflected therein, is an object 26', which in the present illustration is a woman's shoe, said shoe being so positioned, with respect to the adjacent mirrors, that their combined reflections, with the reflection of the table, as seen by the observer, produce the illusion of a third shoe, resting on the table intermediate the two shoes, and behind them. It will be particularly noted that the shoe on the right, as seen in Figure 2, lies in parallel relation with the right-hand mirror, with its toe directed toward the observer, while the other shoe is arranged at approximately right angles to the other mirror, with its toe toward the mirror. When viewed from either side of the center, the observer sees the two shoes, and the complete reflection of the near shoe, while when viewed from the center, he sees partial reflections of both of the shoes, simultaneously in the mirrors,

which produce the illusion of the third shoe, and at the same time sees the two shoes which lie upon the table or shelf.

In each of the side compartments 12 is arranged 5 a chair 33, and in the rear portion of the central compartment 11, behind the mirrors, is a third chair 34, the lower portion of which is visible, at all times, below the table 26, while the upper portion is, under certain conditions, completely hidden from the view of the observer, by 10 the said transparent mirrors. The chairs 33 are so positioned, with respect to the rear chair 34, and the mirrors, that the upper portions of said side chairs will be reflected in the mirrors to produce the illusion of the upper portion of the rear 15 chair being seen. Thus the observer sees the lower portions of the chair 34, below the table 26, and the reflections of the upper portions of the chairs 33, which produce the illusion of a 20 complete chair at the rear of the cabinet.

Depending from the front edge of the table 26 is a panel 36, which serves to conceal, from the eye of the observer, certain parts of the rear chair 34, and parts of the person occupying the 25 same, as well as the entire lamp 31, which is supported on the lower face of the table, adjacent the front edge thereof.

When the upper light 21 is extinguished, the portion of the cabinet, behind the mirrors, will 30 be in darkness, while the front portion thereof, and the side compartments, will be illuminated, by means of the lights 24, 31, and 22, whereby the side chairs, and the two shoes will be reflected in the mirrors.

35 The lower portion of the rear chair 34 will also be illuminated by the lamp 31. The upper portion of the rear chair will be concealed from view, but the reflections of the upper portions of the side chairs 33 will supply, to the observer, the missing upper portion of said rear chair, so that he appears to see the entire rear chair.

While the parts are in the conditions above described, a woman enters the rear portion of the compartment 11, from the side of the cabinet, and completely out of view of the observer, except for her legs, and seats herself on the chair 34, whereupon her feet and legs become visible below the table 26, while her upper portion is hidden behind the mirrors. The shoes 40 are also within the view of the observer, together with the reflected third shoe. The person proceeds to change her shoes and stockings, and to rise and walk around, or assume poses, for the purpose of displaying the shoes and stockings, 45 which are fully illuminated, and in plain view beneath the table, while the upper portion of the woman is completely hidden, due to the non-transparency of the mirrors, at that time. When the person seats herself on the chair 34, the reflections of the backs of the chairs 33 will be seen. The person now turns on the light 21, which illuminates her upper portion, whereupon the entire body and legs are seen, but with the comparatively faint view of the chair back apparently visible through her body. This is due to the fact that the lamp 21 has a greater luminosity than the other lamps. However, the said other lamps are of sufficient luminosity to 50 maintain the reflections of the side chairs, so that the back of the rear chair 34 may appear to be seen through the person's body. The person at the rear of the mirrors may thus cause her upper portion to appear and disappear at 55 will.

It is to be particularly noted that the lamps 22, 24, and 37 remain lighted, at all times, which adds greatly, to the illusion.

Thus two illusions take place, at the same time, the illusion of the three shoes on the table, and the bodyless legs, which are always in view below the table.

What is claimed is:

1. An illusion device comprising a cabinet having a central compartment provided with a sight opening, a pair of angularly disposed mirrors mounted in said compartment, and identically appearing objects each positioned in such relation to one of said mirrors that the combined reflections in the mirrors of the objects produce the illusion of another object of the same appearance. 10

2. An illusion device comprising a cabinet, a support spaced from the bottom of the cabinet, transparent mirrors on the support, identically appearing objects on the support each arranged with relation to a mirror whereby the combined reflections in the mirrors of said objects will produce the illusion of another like object, an object in the rear of said mirrors and partly visible below said support, and means for illuminating the last named object at times. 20

3. An illusion device comprising a cabinet having a central compartment and lateral compartments opening into the central compartment, a table supported in the central compartment between the lateral compartments, transparent angularly meeting mirrors supported on and producing a reflection of the table, identically appearing objects in the lateral compartments and positioned to produce reflections in the mirrors, an object in the central compartment behind said mirrors, a part of the object in the central compartment being constantly visible below said table, the combined reflections in the mirrors of the upper portions of the objects in the lateral compartments producing the illusion of the upper portion of the rear object, identically appearing objects on said table positioned to produce reflections in the mirrors and in such relation to the mirrors that their combined reflections therein produce the illusion of another object on the table, and a lighting system constructed and arranged to permit the object behind the mirrors to be seen therethrough at times. 30

4. An illusion device including a cabinet having a sight opening, a support in the cabinet, angularly disposed transparent mirrors on the support and reflecting the same, identically appearing objects on the support, each arranged with relation to a mirror to reflect therein and being so positioned that the combined reflections of the objects and the reflection of the support will produce the illusion of another like object on the support. 40

5. An illusion device comprising a cabinet having a sight opening, a pair of angularly disposed glass panels mounted in said cabinet, said panels being adapted to reflect and to be transparent, identically appearing objects each positioned in such relation to one of said panels that the combined reflections of the objects produce the illusion of another object of the same appearance, means for illuminating said objects, an object in position to be seen through the panels, and means for illuminating said last named object at times. 50

6. An illusion device comprising a cabinet having a central compartment provided with a sight opening, side compartments opening into said 60

central compartment, a pair of angularly disposed transparent mirrors in the central compartment, identically appearing objects in the side compartments, said objects being in a position to produce reflections thereof in the mirrors and to produce, cooperatively, by reflecting in said mirrors, the illusion of a third object, an object behind the mirrors, and a system of lights to cause reflections of the first-named objects in the mirrors, and to permit the object behind the mirrors to be seen therethrough at times. 5
